INCANDESCENT LAMP WITH DIFFUSING
LAMELLÆCarl Weidner, Berlin, Germany, assignor to Paul
H. von Schele, Chicago, Ill.

Application August 31, 1931, Serial No. 560,527

2 Claims. (Cl. 240—48.6)

The invention relates to incandescent lamps and more particularly to incandescent lamps provided with diffusing lamella.

The object of the invention is to provide for means by which the rays of light of a luminous source such as for an automobile headlight are intercepted, diffused and so influenced as to their effect that they do not dazzle an observer, but without the luminous power being diminished in the least.

Devices intended for attaining this aim have been already known and consist in that the source of light is surrounded by reflecting blades of various shape and adjustment, so-called lamella, the effect of which however is rather slight or even adversely affects the luminous power, as their independent arrangement, for instance at the lamp socket or the reflector requires a definite distance of their bodies from the source of light in order that the incandescent lamp is not liable to be damaged. On account of this independent arrangement it is necessary to provide for separate holders increasing the cost of production.

According to the present invention and in contrast to the devices already known the lamella are fastened directly to the incandescent lamp or to the glass guard thereof so that the said lamella directly surround the lamp or the guard without being clear off. In case the lamella are not integral with the glass guard of the incandescent lamp, they may be slid over as a self-contained bundle and, if required, changed without the incandescent lamp being removed which is important when the light is to get another colour.

The following is given as an example and described with reference to the drawing attached which constitutes part of this application.

Fig. I thereof shows a lamp with lamella slid over;

Fig. II is a top plan view of a lamp provided with the lamella referred to;

Figure III is a cross-section taken on the line III—III of Figure IV; and

Figure IV is a longitudinal section taken on the line of one of the lamella.

Over the source of light or incandescent lamp 1 is slipped a bundle of lamella which bundle consists of single lamella 2 wound or helically formed and made of burnished light metal or another suitable material. The said bundle is supported by the glass guard of the incandescent lamp and secured thereon by a belt laid around the lamp base and made of spirally wound wire or the like.

On account of the shape of the lamella and the elasticity of the spiral belt 3, the first will be pressed against the glass guard so that a direct contact is being maintained. It is also possible to cast lamella composed of a material other than glass integral with the glass guard and so to ensure the tight contact between lamella and glass respectively.

The lamella 2 are desirably formed of thin normally rigid but slightly flexible opaque polished metal strips and are held together at their forward ends as here shown by a relatively small ring 4 which passes loosely through suitable holes in the lamella. A small finishing button 5 may be carried at this end, prongs 6 on the button being passed through the ring after the lamella are secured thereto and bent apart to retain the button in place. The lamella thus converge at their forward ends upon the axis of the lamp, and the bulb is substantially unobstructed except for the lamella in the region adjacent its axis. At their rear ends, the lamella are secured to the spring belt 3, in this instance by having slots 7 hooked into the spring, thus preventing the lamella from falling apart at their rear ends while at the same time maintaining them in resiliently spaced apart relationship about the axis. So constructed and arranged, the bundle of lamella can be spread apart at its rear end to be slipped over the glass guard or bulb 1 of the lamp, the resilient belt expanding for this purpose and then contracting to cause the lamella to grip the bulb.

As clearly shown by the drawing, it will be noted that each of the lamella upstands from the surface of the bulb at an angle less than normal to said surface, particularly at the forward end of the bulb, so that each of the lamella has a somewhat forwardly as well as laterally directed surface, which diffuses the light from the bulb not only laterally but forwardly of the bulb, each of the lamella being bent longitudinally in an ogee curve to enhance this effect. The lamella being desirably metallic and in contact with the lamp bulb for substantially their entire length, serve also as radiating fins which serve to keep the lamp bulb cool and thus lengthen its life.

What I claim as my invention, and desire to secure by Letters Patent is:—

1. In light-diffusing means for an incandescent lamp, the combination of a plurality of separated reflecting lamella spirally and somewhat radially disposed about an axis and converging at their forward ends substantially on said axis, each of the lamella being bent longitudinally in an ogee

curve whereby the lamellæ have surfaces directed forwardly of said axis as well as laterally thereof; relatively small retaining means at the forward ends of the lamellæ to which the lamellæ are anchored, whereby the region adjacent said axis is substantially unobstructed except for said lamellæ, and means at the rear of the lamellæ maintaining them in spaced-apart relation about said axis.

- 10 2. In a light-diffusing device for automobile headlights provided with an incandescent lamp bulb, the combination including a relatively small retaining ring adapted to be disposed concentric with the axis of the bulb at the forward end

thereof; a plurality of reflecting lamellæ each having a hole therein at its forward end loosely receiving said ring therethrough, said lamellæ being spirally directed from said ring rearwardly thereof; and resilient means at the rear of the lamellæ maintaining them in spaced-apart relation but permitting the lamellæ to be radially spread apart on said ring to be readily passed over the bulb, and thereafter to be directly supported by the bulb in partially upstanding relation thereto and with one edge of each of the lamellæ contacting therewith.

CARL WEIDNER.
